UNITED STATES PATENT OFFICE.

GEORGE G. WHITNEY, OF DETROIT, MICHIGAN.

INTERNAL-GRINDING MACHINE.

1,249,871.

Specification of Letters Patent. Patented Dec. 11, 1917.

Application filed March 22, 1917. Serial No. 156,723.

To all whom it may concern:

Be it known that I, GEORGE G. WHITNEY, a citizen of the United States of America, residing at Detroit, in the county of Wayne 5 and State of Michigan, have invented certain new and useful Improvements in Internal-Grinding Machines, of which the following is a specification, reference being had therein to the accompanying drawings.

10 This invention relates to internal grinding machines, turret lathes, and boring machines, and my invention aims to provide a manually fed machine wherein simple and effective means are employed, in a manner as 15 hereinafter set forth, to facilitate the operations in connection with the machines, particularly the feeding operation and that of restoring the machine to normal condition.

20 My invention further aims to furnish a machine of the above type with an automatically actuated brake mechanism for stopping or starting the movement of a headstock when being returned to normal position, thus 25 obviating the necessity of an operator paying any attention to the headstock or the power of the machine after having started the headstock to or from its normal position.

My invention further aims to provide a 30 machine of either type above mentioned wherein the driving means of the work-holder is automatically controlled.

My invention still further aims to accomplish the above and other results by a machine having many features which contribute to successful, economical, and expeditious operations in connection therewith, and the machine will be hereinafter more fully described and then claimed.

40 Reference will now be had to the drawings, wherein—

Figure 1 is a front elevation of the machine;

Fig. 2 is an end view of the machine;

45 Fig. 3 is a longitudinal sectional view of the headstock of the machine, and

Fig. 4 is an enlarged vertical sectional view of an automatic clutch throwing device.

50 In describing my invention by aid of the views above referred to, I desire to point out that the same are merely illustrative of the machine as now actually used, and I do not care to confine myself to the precise construction and arrangement of parts shown. The following description is therefore to be

broadly construed as including such substitute constructions and arrangements of parts which are the obvious equivalent of those to be hereinafter referred to. 60

In the drawing, 1 denotes a machine bed or frame and slideable on top thereof is a bed plate 2 of a headstock 3. The lower face of the bed plate 2 has a longitudinal rack 4 and meshing therewith is a pinion 5 carried by a shaft 6, journaled in a bearing 7, carried by the front wall of the frame 1. The outer end of the shaft 6 has a large hand wheel 8 which permits of an operator or attendant of the machine rapidly revolving the shaft 6 to feed the bed plate 2 longitudinally of the frame 1. 65

9 denotes the base member of a tool carriage 10 and said base member spans or bridges the bed plate 2 and is suitably connected to the sides of the frame 1, as at 11. The tool carriage 10 can be adjusted transversely of the base member 9 by the usual feed screw mechanism, generally denoted 12, and said tool carriage has a spindle 13 provided with a pulley 14 at one end thereof and a grinding head 15, drill or operating instrument, at the opposite end thereof. The grinding head 15 is of the conventional form, for instance an emery wheel, and is adapted for internal grinding of a piece of work carried by the headstock 3. 75 80 85

16 denotes a drive shaft arranged longitudinally of the frame 1 and 17 denotes a driven shaft in a horizontal plane with the shaft 16 and journaled in suitable bearings 18 carried by the frame 1. The driven shaft 17 has fixed and loose pulleys 19 so that said shaft may be driven by a belt from a suitable source of power, and a belt shifting device, generally designated 19 is arranged to control the operation of the driven shaft 17 relative to its source of power. 90 95

20 denotes a large belt wheel on the driven shaft 17 and above this large belt wheel, on the tool carriage 10, are brackets 21 supporting the shaft having a small belt wheel 22 and a large belt wheel 23. Trained over the large belt wheel 23 and the small pulley 14 is a belt 24 and trained about the large belt wheel 20 of the driven shaft 17 and small belt wheel 22 is a belt 25. Engaging the belt 25 is a belt tightening device generally designated 26. 100 105

27 and 28 denote stepped or cone pulleys on the shafts 16 and 17 respectively, and trained about these pulleys is a belt 29 that

may be shifted to increase or decrease the speed of the shaft 16 relative to the speed of the driven shaft 17 by a belt shifting mechanism 30 operable at the front wall of the frame 1. The belt shifting mechanism 30 may be manually adjusted and set so as to obtain a desired speed in connection with the drive shaft 16. The stepped pulley 27 of the shaft 16 is loose thereon and is adapted 10 to be fixed for rotation with the shaft 16 by a clutch 31 of a conventional form. The clutch 31 is operated by the short arm 32 of a rock shaft 33 arranged transversely of the frame 1 and on the lower end of the arm 32 15 is an adjustable brake shoe 34 adapted to engage a brake wheel 35 on the shaft 16, so that after the clutch 31 is thrown out and the shaft 16 independent of the driven shaft 17, the rotation of the drive shaft 16 may be 20 retarded and eventually stopped.

36 denotes a long arm or lever on the front end of the rock shaft 33 and said arm is pivotally connected, as at 37, to an adjustable plunger 38 operable in a cylinder 39 carried by the frame 1. The plunger 38, within the cylinder 39, has a head 40, and engaging said head is a coiled compression spring 41 adapted to hold the plunger 38 normally elevated, and adapted to automatically throw in the clutch 31. The tension of the spring 41 may be increased or decreased by an adjustable cylinder plug 41a.

42 denotes a cam member carried by the bed plate 2 of the headstock 3 and this cam member is adapted to impinge against the upper end of the plunger 38 and gradually lower said plunger, so that the clutch 31 is automatically thrown out when the headstock 3 assumes normal position.

40 When the cam member 42 recedes by shifting the headstock toward the tool carriage, the spring 41 automatically throws in the clutch 31, so that the workholder is revolved.

45 43 denotes a long pulley on the drive shaft 16 and 44 is a pulley of the headstock 3 which is driven from the long pulley 43 by a belt 45. The headstock 3, as best shown in Figs. 1 and 3 has a pneumatic or otherwise actuated chuck or workholder 46 and said headstock is adapted to be moved to and from the tool carriage by the manually actuated feed mechanism including the elements 4 to 8 inclusive. The headstock may 50 be carefully moved toward the tool carriage so that the grinding head or emery wheel 15 may operate upon a piece of work held by the chuck or workholder 46 and after the grinding operation has been performed, 55 the operator or attendant of the machine may give the hand wheel 8 a whirl or sufficient impetus to carry the headstock away from the tool carriage. In doing so, the operator or attendant of the machine need 60 not pay any attention to the return move- 65 ment of the headstock, as the cam member 42 automatically throws out the clutch 31 and the brake shoe 34 is applied to the brake wheel 35, thus causing a cessation in the operation of the drive shaft 16 while the shaft 17 is driven. As the workholder or chuck is brought to a standstill by the brake mechanism, the cam member 42 has limited the return movement of the headstock and another piece of work can be easily placed 70 in the chuck or workholder or other adjustments made. When the hand wheel 8 is turned to feed the workholder toward the grinding head, the cam 42 releases the plunger 38 and the spring 41, which has 75 been placed under compression, now expands and in so doing elevates the plunger and automatically throws in the clutch 31, so that the workholder will be driven to permit of the grinding head operating upon a 80 piece of work.

What I claim is:—

1. A machine of the type described comprising a frame, a reciprocable bed plate on said frame, manually actuated means for reciprocating said bed plate, a tool carriage, a headstock carried by said bed plate and provided with a workholder and adapted to be placed in operable relation to said tool carriage, a drive shaft carried by said frame 95 and adapted for operating said workholder, a clutch controlling the operation of said drive shaft, means actuated by a return movement of said headstock adapted to throw out said clutch, and means brought 10 into action by an outward movement of said clutch to cause a cessation in the movement of said drive shaft.
2. A machine of the type described comprising a frame, a tool carriage, a headstock 10 movable to and from said tool carriage, manually actuated means for moving said headstock, a drive shaft carried by said frame for operating said headstock, a clutch associated with said drive shaft for controlling the operation thereof, a cam member movable with said headstock, and means actuated by said cam member for throwing out said clutch and causing a cessation in 11 the operation of said headstock.
3. A machine of the type described comprising a frame, a tool carriage, a headstock movable to and from said tool carriage, manually actuated means carried by said frame adapted for moving said headstock to 12 and from said tool carriage, a drive shaft carried by said frame for operating said headstock, a clutch associated with said drive shaft, a cam carried by said headstock, means actuated by said cam adapted for 12 throwing out said clutch, and a brake mechanism brought into action by an outward movement of said clutch adapted to retard the movement of said drive shaft.
4. A machine of the type described com- 13

prising a tool carriage, a headstock movable to and from said tool carriage and provided with a revoluble workholder, means for revolving the workholder of said headstock, means for moving said headstock to and from said tool carriage, and means including a clutch automatically actuated by a return movement of a cam member carried by said headstock for controlling the 10 operation of the workholder revolving means.

5. A machine of the type described comprising a frame, a tool carriage carried thereby, a headstock movable to and from said tool carriage and provided with a revoluble workholder, a drive shaft support-

ed by said frame, means including a clutch for driving said shaft, means for imparting movement to the workholder of said headstock from said drive shaft, a cam member carried by said headstock, and means actuated by said cam member adapted to simultaneously cause a cessation in the movement of said headstock and the rotation of the workholder thereof.

In testimony whereof I affix my signature in the presence of two witnesses.

GEORGE G. WHITNEY.
